COMBINED DOOR HANDLE AND LOCK HOUSING ENSEMBLE

William J. Horgan, Jr., Pittsburgh, Pa., assignor to
Blumcraft of Pittsburgh, Pittsburgh, Pa.

Original design application June 1, 1970, Ser. No. 23,251,
now Patent No. 223,796, dated June 13, 1972. Divided
and this application July 15, 1971, Ser. No. 163,128

Term of patent 14 years

Int. Cl. D8—07

U.S. Cl. D8—138

FIG. 1 is a perspective view of a combined door handle and lock housing ensemble embodying my invention shown mounted on a door which is shown in phantom;

FIG. 2 is an enlarged right side view taken as indicated by the lines and arrows 2—2 in FIG. 1;

FIG. 3 is an enlarged rear elevation of the embodiment shown in FIG. 1;

FIG. 4 is a top view taken as indicated by the lines and arrows 4—4 in FIG. 3; and

FIG. 5 is a bottom view taken as indicated by the lines and arrows 5—5 in FIG. 3.

The shading employed does not connote actual appearance, but is an expedient to best illustrate the shape of the handle.

The door shown in phantom lines forms no part of the design and has been included for purposes of illustrating the environment only.

CROSS REFERENCE TO RELATED APPLICATION

This application incorporates by reference and is a division of my prior copending application, Ser. No. D. 23,251, filed June 1, 1970 now Patent No. D. 223,796, June 13, 1972 and discloses and claims subject matter disclosed and claimed therein and in the application cross-referenced therein.

I claim:

The ornamental design for a combined door handle and lock housing ensemble, as shown and described.
